FUEL INJECTION NOZZLE

Ben G. Parsons, Detroit, Mich., assignor to American Bosch Corporation, Springfield, Mass., a corporation of New York

Application February 26, 1942, Serial No. 432,449

4 Claims. (Cl. 299—107.1)

This invention relates to fuel injection nozzles of the fixed-pintle, or permanently-open, airless type intended to be mounted in the cylinders of internal combustion engines or in their intake manifolds for spraying therewith during the proper period of the engine cycle the liquid fuel charges delivered under pressure by associated fuel injection pumps.

The primary object of the invention is to provide simple, inexpensive, compact, economical and durable nozzles of this kind, which are capable of being readily converted to precisely predetermined adjustments to produce at will at comparatively low injection pressure different forms of atomized sprays of fuel as required for different engines and for different engine performance.

Other objects and advantages will be obvious from the following disclosure of several embodiments of nozzles within my invention, taken in conjunction with the accompanying drawing showing, as an example, low pressure nozzles without check valves for gasoline injection. In the drawing,

Fig. 1 is a central vertical section of one form of nozzle on an enlarged scale; Fig. 2 is a section on line 2—2 of Fig. 1; and Figs. 3 and 4 are central sections of two other forms of nozzles, partly broken away.

Referring first to Figs. 1 and 2, the nozzle body 1 of nickel steel alloy has a polygonal wrench grip 2 and a threaded end 3 for fastening the body in a threaded hole at the proper place in an engine cylinder or intake manifold. The cylindrical bore of the body is threaded near its top at 4 and is smooth throughout its unthreaded portion 5. The pintle 6, also of nickel steel alloy, is screw-threaded at 7 for a nut fitting for securing in place a pipe from the gasoline injection pump (not shown), and also is screw-threaded to fasten it in the body at 4 by screwing, using the wrench grip at 2, the pintle into the predetermined longitudinal position in the bore of the body as shown, the cylindrical shank of the pintle having a slight clearance with the smooth portion of the bore of the nozzle body. Between the adjacent shoulders of the two wrench grips 2 and 8, is a soft copper washer 9 of the desired thickness as hereinafter described. Near the lower end of the pintle is a circumferential groove 11, of V-shape in cross section equal to an included angle of about 90°, into which open the transverse cross bores 12. Below the cross bores is an end wall 13 of reduced diameter relatively to shank 10 of the pintle, so as to provide an annular clearance space at 15, 55

of considerable area in cross section, between the end wall and the bore of the nozzle body. The central longitudinal bore 14 extends from the top of the pintle to the place of juncture of the cross bore at 16, so as to furnish communication for the fuel to the groove 11 from the pipe fastened at the top of the pintle.

The embodiment of Fig. 3 is the same as the foregoing, except that the gasket 17 is thinner, giving a reduced length to the annular space at 18, and the V-section of the groove 19 has a lesser included angle equal in this case to about 30°.

The embodiment of Fig. 4 is the same except that the gasket 20 is thicker than the gaskets of the foregoing embodiments, giving a greater length to the annular space at 21, and the V-section of the groove 22 is most obtuse of all equal in this case to an included angle of about 135°.

It will be observed in these three embodiments, that the pintle 10 is not spring-pressed in the nozzle body 1, but is fixed therein and is permanently open to the engine cylinder or intake manifold when installed. The pressure on the gasoline is, therefore, that merely required to provide the appropriate spray from the nozzle and may accordingly be less than if also required to lift the pintle against a spring. Also it will be observed that since all parts of the nozzle are operatively stationary, or fixed to each other upon assembly, there is no appreciable wear and therefore there is a greater effectiveness and predetermined accuracy throughout a longer period of service. Also it will be obvious that close fits and tolerances are not required except as to the included angle of the circumferential V-groove and for the thickness of the gasket between the pintle and nozzle body which also can be preselected. Furthermore, it will be obvious in all embodiments that the large area and length of the substantial fit between the pintle and nozzle body, as compared with the opening from the V-groove to the engine, tends to reduce the leakage and accordingly tends to improve the economy and efficiency of injection. The simplicity, inexpensiveness and compactness of the nozzle results naturally from the elimination of all but the irreducible number of simple parts for the purpose, all fixed when in assembled position.

As a result of predetermined variations of the included angle of the V-shaped groove near the end of the pintle, and the length of the annular space at the end wall thereof, the gasoline may be sprayed into the engine at any angle desired in the form of a thin sheet, somewhat cone shaped

and of desired thickness, thereby giving good atomization at low line pressure. For a small bore engine cylinder with a long piston stroke, a small included angle as shown in Fig. 3 is preferable, while for a larger bore and shorter stroke, a larger included angle is preferred as in Figs. 1 or 4. Thus by selecting the pintle with predetermined included angle in its V-groove as 11, 19 or 22 in accordance with the bore and stroke of the engine, and by selecting a washer of proper thickness as 9, 17 or 20 to predetermine the position of the end wall of the pintle relatively to the lower edge of the nozzle body, the angle of the spray cone, its degree of atomization and its thickness may be accurately predetermined. These and other predetermined characteristics of the spray are maintained throughout long periods of service as a result of the elimination of wear of parts and the absence of spring seats, leak-off connections and small injection holes. Furthermore, with the body 1 fastened in place in the engine, different washers and pintles with different forms of V-grooves may be readily tried out in predetermining the characteristics of the nozzle for the best engine performance in each case.

It will be obvious that many modifications may be made within the scope of the invention. For instance, pintles having peripheral grooves of other form or V-grooves with still other included angles may be used, with terminal portions which may have different diameters and axial length, and different locations with respect to the end of the nozzle body; also still other thicknesses of washers between the pintle and body may be used, and likewise other forms of longitudinal bores and other forms of transverse bores whether single or crossing. Also ball or other forms of check valves may be incorporated in the nozzles or in the pump associated therewith to check the back flow of the fuel or otherwise. These and other modifications are intended to be covered within the broad interpretation of the appended claims.

Having thus described my invention, what I claim is:

1. In a fuel injection nozzle of the permanently-open, airless type for association with a fuel injection pump and an internal combustion engine; a nozzle body adapted to be fastened in the engine and having a single longitudinal bore; a pintle which is fastened to the nozzle body in predetermined position in said bore and has an upper portion closely fitting therein, and which has a terminal portion of smaller outer diameter than the diameter of the end portion of said bore so as to form at all times with the end portion of the nozzle body an annular space of predetermined length for the injection of fuel therethrough, a peripheral groove arranged above and adjacent said terminal portion and opening into said annular space, at least one transverse fuel bore communicating with said peripheral groove,

and a single longitudinal fuel bore communicating with said transverse bore.

2. In a fuel injection nozzle of the permanently-open, airless type for association with a fuel injection pump and an internal combustion engine; a nozzle body adapted to be fastened in the engine and having a single longitudinal bore; a pintle which is fastened to the nozzle body in predetermined position in said bore and has an upper portion closely fitting therein, and which has a terminal portion extending below the nozzle body and having a smaller outer diameter than the diameter of the end portion of said bore so as to form at all times with the end portion of the nozzle body an annular space of predetermined length for the injection of fuel therethrough, a peripheral groove arranged above and adjacent said terminal portion and opening into said annular space, at least one transverse fuel bore communicating with said peripheral groove, and a single longitudinal fuel bore communicating with said transverse bore.

3. In a fuel injection nozzle of the permanently-open, airless type for association with a fuel injection pump and an internal combustion engine; a nozzle body adapted to be fastened in the engine and having a single longitudinal bore; a pintle which is fastened to the nozzle body in predetermined position in said bore and has an upper portion closely fitting therein, and which has a terminal portion of smaller outer diameter than the diameter of the end portion of said bore so as to form at all times with the end portion of the nozzle body an annular space of predetermined length for the injection of fuel therethrough, a peripheral V-groove of predetermined included angle arranged above and adjacent said terminal portion and opening into said annular space, at least one transverse fuel bore communicating with said peripheral groove, and a single longitudinal fuel bore communicating with said transverse bore.

4. In a fuel injection nozzle of the permanently-open, airless type for association with a fuel injection pump and an internal combustion engine; a nozzle body adapted to be fastened in the engine and having a single longitudinal bore; a pintle which is fastened to the nozzle body in predetermined position in said bore and has an upper portion closely fitting therein, and which has a terminal portion of smaller outer diameter than the diameter of the end portion of said bore so as to form at all times with the end portion of the nozzle body an annular space of predetermined length for the injection of fuel therethrough, a peripheral V-groove with an included angle between 30° and 135° arranged above and adjacent said terminal portion and opening into said annular space, at least one transverse fuel bore communicating with said peripheral groove, and a single longitudinal fuel bore communicating with said transverse bore.
